UNITED STATES PATENT OFFICE

140,565

DESIGN FOR A HOE HEAD

Richard Harte, Williamstown, W. Va., assignor to
Ames Baldwin Wyoming Co., Parkersburg,
W. Va., a corporation of Delaware

Application May 9, 1944, Serial No. 113,527

Term of patent 14 years

(Cl. D35—2)

To all whom it may concern:

Be it known that I, Richard Harte, a citizen of the United States, residing at Williamstown, County of Wood and State of West Virginia, have invented a new, original, and ornamental Design for a Hoe Head, of which the following is a specification, reference being had to the accompanying drawing, forming a part thereof.

In the drawing:

Fig. 1 is a front perspective view of a hoe head showing my new design; and

Fig. 2 is a rear perspective view thereof.

The design is characterized by the central upwardly directed arris along the length of the gooseneck of the hoe head (through which the

blade is secured to the handle), which arris is defined by the intersection of two upwardly and outwardly facing diagonal surfaces, the arris continuing over the forward face of the blade as an arris of a rib which extends from the upper margin of the blade over the front face of the blade and tapers in width and depth towards the edge of the blade and the lateral boundaries of said surfaces merging into the base of said rib at the upper margin of the blade.

I claim:

The ornamental design for a hoe head, as shown and described.

RICHARD HARTE.
